[57] CLAIM

The ornamental design for a merchandising machine, substantially as shown and described.

DESCRIPTION

FIG. 1 is a front elevation of a merchandising machine showing my new design.

FIG. 2 is a top plan thereof;

FIG. 3 is a right side elevation, drawn on a reduced scale, the left side elevation being a mirror image thereof;

FIG. 4 is a rear elevation, drawn on a reduced scale; and

FIG. 5 is a section, taken along the line 5—5 of FIG. 1.
